UNITED STATES PATENT OFFICE

114,980

DESIGN FOR A CAP

Frank J. Wengen, Milwaukee, Wis., assignor to Eagle Knitting Mills, Inc., Milwaukee, Wis., a corporation of Wisconsin

Application January 3, 1939, Serial No. 82,129

Term of patent 7 years

To all whom it may concern:

Be it known that I, Frank J. Wengen, a citizen of the United States, residing at Milwaukee, in the county of Milwaukee and State of Wisconsin, have invented a new, original, and ornamental Design for a Cap, of which the following is a specification, reference being had to the accompanying drawing, forming part thereof.

In the drawing:

Fig. 1 is a perspective view of the cap showing
my new design;

Fig. 2 is a front view thereof

I claim:

The ornamental design for a cap, as shown.

FRANK J. WENGEN.
